(57) **CLAIM**

The ornamental design for a display screen or portion thereof with graphical user interface, as shown and described.

DESCRIPTION

FIG. 1 is a front view of a display screen or portion thereof with graphical user interface showing my new design according to a first embodiment; and,
FIG. 2 is a front view of a display screen or portion thereof with graphical user interface showing my new design according to a second embodiment.

The outer perimeter shown in evenly-spaced dashed broken lines in the figures depicts a display screen or portion thereof and forms no part of the claimed design. The remaining evenly-spaced dashed broken lines in the figures depict portions of the graphical user interface that form no part of the claimed design.

1 Claim, 2 Drawing Sheets
